(57) **CLAIM**

The ornamental design for a hollow fiber membrane module as shown and described.

DESCRIPTION

FIG. 1 is a perspective view of a hollow fiber membrane module showing our new design;

FIG. 2 is a front view thereof;

FIG. 3 is a rear view thereof;

FIG. 4 is a left side view thereof;

FIG. 5 is a top view thereof;

FIG. 6 is a bottom view thereof; and,

FIG. 7 is an enlarged left side view thereof.

The broken lines depict portions of the hollow fiber membrane module in which the design is embodied that are not considered part of the claimed design.

1 Claim, 7 Drawing Sheets
